UNITED STATES PATENT OFFICE

121,992

DESIGN FOR A LANTERN REFLECTOR

Earl G. Griffith and Howard L. Johnson,
Jamestown, N. Y.

Application May 28, 1938, Serial No. 77,460

Term of patent 14 years

To all whom it may concern:

Be it known that we, Earl G. Griffith and Howard L. Johnson, citizens of the United States, residing at Jamestown, in the county of Chautauqua and State of New York, have invented a new, original, and ornamental Design for a Lantern Reflector, of which the following is a specification, reference being had to the accompanying drawing forming part thereof, and in which the figure is a perspective view of a lantern reflector showing our new design.

The characteristic features of our design reside in an arcuate reflector of the configuration disclosed having open ended spring clips joined to opposite ends thereof, the clips being substantially of the configuration and positioned as shown.

We claim:

The ornamental design for a lantern reflector, substantially as shown and described.

EARL G. GRIFFITH.
HOWARD L. JOHNSON.
